(57) **CLAIM**

The ornamental design for a plastic food bowl, substantially as shown and described.

DESCRIPTION

FIG. 1 is a top, perspective view of an embodiment of a design for a plastic food bowl.

FIG. 2 is a bottom, perspective view of the embodiment of a design of FIG. 1.

FIG. 3 is a top, plan view of the embodiment of a design of FIG. 1.

FIG. 4 is an elevation view of the left side of the embodiment of a design of FIG. 1.

FIG. 5 is an elevation view of the right side (identical to the left side in FIG. 4) of the embodiment of a design of FIG. 1.

FIG. 6 is a bottom, plan view of the embodiment of a design of FIG. 1.

FIG. 7 is an elevation view of the front side (identical to the left side of FIG. 4 and the right side of FIG. 5) of the embodiment of a design of FIG. 1; and,

FIG. 8 is an elevation view of the back side (identical to the left side of FIG. 4, the right side of FIG. 5, and the back side of FIG. 7) of the embodiment of a design of FIG. 1.
